UNITED STATES PATENT OFFICE.

EVERETT E. BUSSEY, OF MALDEN, MASSACHUSETTS, ASSIGNOR TO ALEXANDER P. BROWNE, TRUSTEE, OF CAMBRIDGE, MASSACHUSETTS.

DISPENSER FOR LIQUID SOAP AND THE LIKE.

1,173,481.

Specification of Letters Patent. Patented Feb. 29, 1916.

Application filed January 31, 1914. Serial No. 815,662.

To all whom it may concern:

Be it known that I, EVERETT E. BUSSEY, a citizen of the United States, and a resident of Malden, in the county of Middlesex 5 and State of Massachusetts, have invented a new and useful Improvement in Dispensers for Liquid Soap and the like, of which the following is a specification.

My invention relates to dispensers for 10 liquid-soap and the like and more especially to devices of this character in which a small charge of liquid is delivered by the manual actuation of a valve located at the lower portion of the container.

15 The object of my invention is to improve and simplify the construction of containers for liquids in the manner hereinafter set forth.

One embodiment of my invention is 20 shown in the accompanying drawings in which—

Figure 1 is a vertical central section of a dispenser for liquid embodying my invention. Fig. 2 is a section taken on the 25 line 2—2, and Fig. 3 is a section taken on the line 3—3.

In the particular drawings selected for more fully disclosing the principle of my invention, 1 represents a reservoir or 30 container of glass, metal, or other suitable material provided with a threaded cap 2 and a tubular single piece neck, one end of which projects into the reservoir and the other terminates in a delivery chamber 3. In 35 the present instance I have shown the neck as separate from the reservoir, although it will be obvious that it may be made integral therewith. Any suitable means may be employed for attaching the neck to the reservoir, and in the present instance I provide a nut 5 threaded to the neck for compressing the rubber gasket 6 between the inner wall of the reservoir and said nut, a flange 4 integral with the neck being in engagement with the outside of the reservoir.

Located within the neck and having a sliding fit with the same is a plunger 7 provided with one or more lateral recesses, 50 pockets, or passages 8 for conveying a predetermined quantity or charge of liquid from the reservoir to the delivery chamber 3. Preferably three or more such recesses

are employed, so that the plunger may have three or more points of support on the interior wall 9 of the neck. This is desirable because thereby the plunger is kept in perfect alinement with the valve seat without unduly prolonging the plunger and without lengthening the neck in which it reciprocates. Unless three or more such points of support are provided, the proper seating of the valve 11 on its squared valve seat to close the lower end of the delivery chamber is not always possible, such seating being at best uncertain and the outlet 12 being often partially open. By means of my construction, however, the plunger is always positively guided and the valve always squarely seated, leakage being thereby prevented. The delivery chamber is provided with an outlet 12 through which projects the handle 10 of the plunger, a rubber gasket 11, which surrounds the handle just below its juncture with the plunger, constituting a valve coöperating with a squared valve-seat 11' cut into the lower portion of the chamber 3. The valve seat preferably is formed by counterboring the upper part of the outlet 12, and, as shown, its upright walls are at right angles to its floor. The upper portion of the neck is cut away as shown at 13, 14, leaving two upright standards one of which is shown at 18 and a rim 18' to which is threaded a cap 15 or 80 other suitable device to afford a fixed support for the upper end of the spiral spring 17 surrounding a pin 16 which, if employed, rises from the plunger, said standards 18 constituting means for guiding the plunger 90 in its reciprocal movements and the spaces between said standards ports through which the contents of the reservoir may flow into the upper chamber or cage formed by the standards the rim and the cap. As 95 shown, the spring is tapering in longitudinal section, the spires thereof being of progressively decreasing diameter downwardly, so that when compressed by forcing the plunger up to its full extent, the 100 spires will be nested within the topmost spire and the top of the plunger separated from the underside of the cap 15 by the thickness of the wire by which the spring is formed. This is advantageous as it permits the use of a shorter neck.

2

In devices of this character it is desirable to deliver a small quantity or charge of soap at a time in order to prevent waste and it is preferable to have the delivery chamber air-tight. As will be obvious, the plunger is normally held downward so that the outlet 12 is closed by the gasket 11. The upward movement of the plunger is limited as aforesaid only by the thickness 10 of a single spire or coil of the spring 17 which surrounds the plunger pin. When the plunger is held on its seat, its upper end will be well within the neck 9 and thus the liquid will be prevented from flowing 15 from the reservoir into the delivery chamber, and also liquid in said chamber will be prevented from escaping through the outlet thereof. When the handle is pushed upwardly by the palm of the hand, the pockets 8 are brought into communication with 20 the reservoir through the passages or cut-away portions 13, 14, and upon the release of the handle, the plunger under the action of its spring, will be thrust downward and 25 a charge of liquid thereby conveyed bodily from the reservoir to the chamber. The plunger is then again pushed upwardly as before and a second charge flows into the plunger passage. On the release of the plunger 30 its spring again forces it downward and the liquid charge previously conducted into the air-tight chamber is forced or crowded by the incoming charge out of the chamber past said valve seat, and expelled 35 through the chamber outlet, around the handle and down along the latter into the palm of the hand. The handle in projecting through the outlet assists in conducting and guiding the liquid directly into the palm of 40 the hand. Thus the repeated operation of the handle and its plunger as described takes charges from the reservoir and carries them bodily successively into the delivery chamber. After the first charge has been delivered 45 it will not be necessary in obtaining the next charge to push the plunger upward twice, since a charge will always be in the chamber in readiness to be delivered therewith on the first upward push of the plunger. 50

Heretofore, in liquid soap dispensers, considerable difficulty has been experienced from the drying and clogging of the delivery mechanism, owing, among other reasons, to the fact that such mechanisms have been exposed to the air between operations. By my invention the discharging mechanism is not exposed to the air at any time excepting on the delivery of liquid there-through since the mechanism is inclosed in 60 the air-tight chamber and the ingress of air thereto is effectively prevented by the sealing of the outlet end of the chamber by the plunger valve on the valve seat. As shown 65 herein the liquid charge conveyed by the

plunger passage 8 is not sufficient to completely fill the chamber surrounding the plunger, but there is a volume of air pocketed above the charge resting on the bottom of the chamber above its outlet. This 70 constitutes a fluid seal beneath the upper valve portion of the plunger which closes the entrance between the reservoir and chamber, and effectively prevents any leakage of liquid from said reservoir past said plunger 75 into said chamber. As a result the same volume of liquid charge is always delivered from the chamber. While herein both liquid and air are in the chamber it will be apparent that the seal would exist if either 80 air or liquid were in the chamber. Any tendency to dry or clog the delivery mechanism is further prevented by the fact that said mechanism is continuously surrounded and kept wet by the liquid in the chamber. 85 If there should be at any time an accumulation of dry soap exterior of the valve seat in the annular discharge openings surrounding the handle it is automatically dislodged 90 when the handle is moved upwardly for effecting a discharge operation.

It has been found in practice that devices of this character are liable to leak because the valve on the plunger does not always accurately coöperate with its valve seat. I 95 have eliminated this difficulty by employing such number of passages 8 that the plunger will have at least three points of support on the interior of the neck, thereby insuring the accurate registering of the valve 100 with its seat. It has also been found that reservoirs in liquid soap dispensers are liable to breakage due to temperature changes when the wall bracket engages directly with the reservoir. Accordingly, in 105 the present instance, I have provided a bracket 19 having a wall plate 20 at one end and a two-part clamp 22, 23, at the other, said clamp engaging the neck itself 110 as distinguished from the reservoir, so that the contact will be between metal and metal as distinguished from metal and glass, as is the case where the bracket embraces the lower part of the reservoir itself. The clamp preferably engages the neck between 115 the flanges 4, 21 and the two halves thereof are united by screws 24 threaded into the lugs 25, 26, or in any other suitable manner.

A dispenser such as described above provides a very advantageous construction; it 120 is simple in construction and operation, cheap to manufacture and is not liable to get out of order.

While the dispenser has been described herein as applicable for receiving liquid 125 soap, it will be readily understood that it may be used for delivering perfumery or other liquids or materials.

Having described one embodiment of the invention without limiting the same thereto, 130

what I claim as new and desire to secure by Letters Patent is:

1. A dispenser for liquids comprising in combination a reservoir, a one-piece neck and delivery chamber connected therewith, a plunger provided with a lateral pocket, means whereby said pocket may be brought into communication with said reservoir and chamber successively, a standard secured to said neck, and a spiral spring interposed between said standard and the upper end of said plunger, the spires of said spring being of progressively decreasing diameter, whereby when compressed to its full extent said spires will be nested together. 15
2. A dispenser for liquids comprising in combination a reservoir, a neck integral with and terminating in a discharge chamber connected with said reservoir, a plunger 20 slideable in said neck, said plunger being provided with three or more recesses, whereby the recessed portion of said plunger will have three or more points of support on the interior wall of said neck, said chamber having a squared valve seat cut into the lower portion of the same and a valve on said plunger arranged to coöperate with said valve seat. 25
3. A dispenser for liquids comprising, in combination, a reservoir, a one-piece neck and delivery chamber connected therewith, a plunger provided with a lateral pocket, means whereby said pocket may be brought into communication with said reservoir and chamber successively, spaced members secured to said neck and extending into said reservoir for guiding said plunger during its reciprocal movements, and a spring disposed within said neck for normally retaining said plunger in said delivery chamber. 30
4. A dispenser for liquids comprising, in combination, a reservoir, a one-piece neck and delivery chamber connected therewith, said chamber having a valve seat cut in its lower portion, a plunger provided with a series of pockets and adapted to coöperate with said valve seat, means whereby said pockets may be brought into communication with said reservoir and chamber successively, spaced members integral with said neck and extending into said reservoir for guiding said plunger during its reciprocal movements, and a spring for normally retaining said plunger in contact with said valve seat. 45
5. A dispenser for liquids comprising, in combination, a reservoir, a one-piece neck and delivery chamber connected therewith, said chamber having a valve seat therein, a plunger provided with a lateral pocket and adapted to coöperate with said valve seat, means whereby said pocket may be brought into communication with said reservoir and chamber successively, spaced members secured to said neck and extending into said 50
- reservoir for guiding said plunger during its reciprocal movements, a cap secured to the free ends of said spaced members, and a spring disposed between said members, the upper end of said plunger and said cap 70 for normally retaining said plunger in its valve seat. 55
6. A dispenser for liquids comprising, in combination, a reservoir, a one-piece neck and delivery chamber connected therewith, a plunger provided with a lateral pocket, means whereby said pocket may be brought into communication with said reservoir and chamber successively, spaced plunger-guiding members secured to said neck and extending upwardly into said reservoir, and a spring for normally maintaining said plunger in contact with the lower portion of said delivery chamber. 80
7. A dispenser for liquids comprising, in combination, a reservoir, a neck terminating in a discharge chamber connected with said reservoir and a plunger slideable in said neck, the said plunger being provided with three or more recesses, whereby the recessed portion of said plunger will have at least three points of support on the interior wall of said neck. 85
8. A dispenser for liquids comprising, in combination, a reservoir, a neck terminating in a discharge chamber connected with said reservoir, a plunger slideable in said neck, the said plunger being provided with three or more recesses, whereby the recessed portion of said plunger will have at least three 90 points of support on the interior wall of said neck, the lower portion of said chamber being provided with an outlet counterbored to form a valve seat having its upright walls at right angles to its floor, and a valve on 95 said plunger coöperating with said valve seat. 100
9. A dispenser for liquids comprising, in combination, a reservoir, a neck terminating in a discharge chamber connected with said reservoir, a plunger provided with a pocket and guided by said neck, means whereby said pocket may be brought into communication with said reservoir and chamber successively, the lower portion of said chamber being provided with an outlet counterbored to form a valve seat having its walls at right angles to its floor, and a valve on 110 said plunger coöperating with said valve seat. 115
10. A dispenser for liquids comprising, in combination, a reservoir, a one-piece neck and delivery chamber connected therewith, said chamber having a valve seat cut into its lower portion, a plunger provided with a lateral pocket and adapted to coöperate with said valve-seat, means whereby said pocket may be brought into communication with said reservoir and chamber successively, spaced members for guiding said 125 120
- 130

plunger and extending from said neck into said reservoir, a cross-piece secured to the upper ends of said spaced members, and a spring having its ends bearing respectively against said cross-piece and the upper end of said plunger.

11. A dispenser for liquids comprising in combination a reservoir, a delivery chamber, provided with a neck, secured to said reservoir, said delivery chamber having a valve seat cut into its lower portion, an upper chamber arranged above said neck and extending into said reservoir, said upper chamber being provided with a port 15 through which the contents of said reservoir may flow into said upper chamber, a plunger provided with a lateral pocket and adapted to coöperate with said valve seat, said plunger being arranged for reciprocation in and guidance by said neck and upper chamber, means whereby said pocket may be brought into communication with said reservoir and delivery chamber successively, a member secured to and extending across the top of said upper chamber, and a spring having its ends bearing respectively against said member and the upper end of said plunger.

12. A dispenser for liquids comprising in combination a reservoir, a delivery chamber provided with a neck, said chamber being secured to said reservoir and having a valve seat cut into the lower portion thereof, an upper chamber arranged above said neck and extending into said reservoir, said upper chamber having a closed top and being provided with a port through which the liquid to be dispensed may flow from said reservoir into said upper chamber, a plunger 40 provided with a lateral pocket and adapted to coöperate with said valve seat, said plunger being arranged for reciprocation in and guidance by said neck and upper chamber, means whereby said pocket may be brought into communication with said reservoir and delivery chamber successively, and a resilient member interposed between the top of said upper chamber and the adjacent end of said plunger to normally maintain said plunger in engagement with said valve seat.

13. A dispenser for liquids comprising in combination a reservoir, a delivery chamber provided with a neck, said chamber being secured to said reservoir and having a valve seat cut into the lower portion thereof, an upper chamber arranged above said neck and extending into said reservoir, said upper chamber having a closed top and being provided with a port through which the liquid to be dispensed may flow from said reservoir into said upper chamber, a plunger 55 provided with a lateral pocket and having a shoulder adapted to coöperate with said valve seat, said plunger being arranged for reciprocation in and guidance by said neck

and upper chamber, means whereby said pocket may be brought into communication with said reservoir and delivery chamber successively, and a resilient member interposed between the top of said upper chamber and the adjacent end of said plunger to normally maintain said shoulder in engagement with said valve seat. 70

14. A dispenser for liquids comprising in combination a reservoir, a delivery chamber provided with a neck, said chamber being secured to said reservoir and having a valve seat cut into the lower portion thereof, an upper chamber arranged above said neck and extending into said reservoir, said upper chamber having a closed top and being provided with a port through which the liquid to be dispensed may flow from said reservoir into said upper chamber, a plunger 80 provided with a lateral pocket and carrying a gasket adapted to coöperate with said valve seat, said plunger being arranged for reciprocation in and guidance by said neck and upper chamber, means whereby said pocket may be brought into communication with said reservoir and delivery chamber successively, and a resilient member interposed between the top of said upper chamber and the adjacent end of said plunger to normally maintain said gasket in engagement with said valve seat. 85

15. A dispenser for liquids comprising in combination a reservoir, a one-piece neck and delivery chamber connected therewith, said chamber having an outlet opening, a plunger having a reduced portion intermediate its ends, means whereby the reduced portion may be brought into communication with said reservoir and chamber successively, a cage secured to said neck for guiding said plunger and extending into said reservoir, and a spring disposed between said cage and said plunger for normally retaining said plunger in its lowermost position. 90

16. A dispenser for liquids comprising in combination a reservoir, a one-piece neck and delivery chamber connected therewith, said chamber having an outlet opening, a plunger having a reduced portion intermediate its ends, means whereby said reduced portion may be brought into communication with said reservoir and chamber successively, spaced members extending 100 from said neck into said reservoir for guiding said plunger, a cap having an aperture therein secured to said members, a pin carried by said plunger and passing through the opening in said cap, and a spring arranged about said pin between said cap and 105 plunger for normally retaining said plunger in position to close the outlet opening in the chamber. 110

17. A dispenser for liquids comprising in combination, a reservoir, a one-piece neck 115

and delivery chamber connected therewith, a plunger provided with a lateral pocket, a standard secured to said neck, means whereby said plunger may be reciprocated 5 substantially throughout the entire length of said delivery chamber, neck and standard and for causing said pocket to alternately communicate with said reservoir and chamber, and a spiral spring interposed between said standard and the upper end of 10 said plunger, the spires of said spring being of progressively increasing diameter whereby when compressed to its full extent said spires will be nested together.

15 18. A dispenser for liquids comprising in combination, a reservoir, a one-piece neck and delivery chamber connected therewith, a plunger provided with a lateral pocket, spaced members secured to said neck and 20 extending into said reservoir for guiding said plunger in its reciprocal movements, a spring for normally retaining said plunger in said delivery chamber, and means whereby said plunger may be reciprocated substantially throughout the entire length of 25

said chamber, neck and spaced members and for causing said pocket to alternately communicate with said reservoir and chamber.

19. A dispenser for liquids comprising in combination, a reservoir, a one-piece neck 30 and delivery chamber connected therewith, a plunger provided with a lateral pocket, a cage secured to said neck within which said plunger is adapted to slide and be guided thereby, means for reciprocating said plunger and resilient means disposed within said cage for normally retaining said plunger within said chamber and permitting said plunger to be moved substantially throughout the entire length of said chamber, neck 35 and cage whereby said pocket may be brought into successive communication with said reservoir and chamber.

In testimony whereof, I have hereunto subscribed my name this 30th day of Jan- 40
uary, 1914.

EVERETT E. BUSSEY.
